Leslie G. Eltmann, Portland, Oreg., assignor to Electric Steel Foundry Company, Portland, Oreg., a corporation of Oregon

Application October 17, 1955, Serial No. 540,882

4 Claims. (Cl. 100—272)

This invention relates to a press, and more particularly to a hydraulic type press adapted to receive dies, etc.

An object of the present invention is to provide a press of small and compact arrangement wherein a fast-acting operation can be carried on with low hydraulic pressure and through the use of small cylinders. A further object is to provide a press wherein complete access is provided to the die area and to the dies while at the same time providing the working parts of the press within very small compass. A still further object is to provide a press of unique construction in which the power cylinders are housed within the base of the press and in which the base top provides a fixed jaw or jaw support for dies while also suspending power units within the base for the actuation of a rocker arm carrying a movable jaw adapted to receive dies. Yet another object is to provide a hollow base having a top wall providing a support for suspending power units within the base coacting with toggle levers for the moving of a rocker arm carrying a forwardly-extending movable jaw adapted to receive dies or co-acting with dies carried by the base top, the motor and pump units being carried by a side wall of the base. Other specific objects and advantages will appear as the specification proceeds.

The invention is shown, in an illustrative embodiment, by the accompanying drawings, in which

Figure 1 is a front elevational view of a press embodying my invention; Fig. 2, an enlarged vertical sectional view, the section being taken as indicated at line 2—2 of Fig. 1; Fig. 3, a horizontal sectional view, the section being taken as indicated at line 3—3 of Fig. 2; and Fig. 4, a sectional detail view, the section being taken as indicated at line 4—4 of Fig. 2.

In the illustration given, A designates a hollow base having a top wall A'. The base A has a closed front forward wall 10, and closed side walls 11 and 12. The rear wall of the base is open at 13, as shown best in Fig. 3. The top wall A' is provided along its rear side with three spaced upwardly-extending arms 14, 15 and 16, which are centrally apertured to receive a pivot pin 17.

A rocker arm B is provided with depending spaced flanges 18 and 19 received between the arms 14, 15 and 16, as shown best in Fig. 4, and the flanges 18 and 19 are also apertured to receive the pivot pin 17. The rocker arm B has a forwardly-extending movable jaw 20, adapted to have secured thereto a top die 21 opposed to the die 22 resting upon the forward portion of the base top wall A' which, in effect, constitutes a fixed jaw. The dies 21 and 22 can be seen in Figs. 1 and 2 to be contoured to perform a swaging operation on a metal sleeve such as used in securing the end of a wire rope in forming an eye splice or the like.

I employ the inner chamber of the base casing as a means for housing the working parts of the press, and the operator is shielded from such parts by the front wall 10 of casing A. The top wall A', as shown best in Figs. 2 and 4, is provided with depending web portions

2

23 and 24, on which are suspended hydraulic cylinders 25 and 26. Between the cylinders I provide a division wall 27. The cylinders 25 and 26 are provided each with upwardly-extending spaced ears 28, and a pivot pin 29 extends through the ears 28 and the web members 23 and 24 as well as through the partition wall 27. The cylinders 25 and 26 are each provided with a piston stem 30 extending downwardly from the closure plate 31 of the cylinder. Within each cylinder is the usual piston and communicating with the ends of the cylinder are flexible conduits (not shown) for supplying pressure fluid to the cylinders. Since such structures are well known, a detailed description herein is believed unnecessary.

15 The power piston stem 30 extending from each of the cylinders is provided at its lower end with a sleeve socket 32 engaging a pivot pin 33. Each pivot pin 33 connects a pair of toggle links or toggle levers 34 and 35, which may be of any suitable type or construction. Each inner toggle lever 34 is connected at one end to the front wall 10 of the casing A by means of an elongated pivot pin 36. As shown best in Fig. 3, the wall 10 is provided with a pair of inwardly-extending flanges 37 on each side of the partition wall 27, and the lever 34 is provided 20 with three rearwardly-extending fingers 38 receiving the flanges 37 and pivotally supported thereon by the pin 36. Each of the toggle levers 34 is provided with a solid base portion and with upwardly-extending side rib portions 39. At its other end, each lever 34 is provided 25 with outer flanges 40 apertured to receive the pin 33 and also to receive therebetween the spaced flanges 41 of the lever 35.

30 Each of the levers 35 has also a solid base portion and upwardly-extending reinforcing ribs 42. At its outer end, each lever 35 has a pair of spaced flanges 43 apertured to receive the pivot pin 44 carried by the depending arm 45 of the rocker arm B.

35 Suspended upon one side wall of the casing A is the motor 46 which drives through the belt 47 the pump 48. Suitable controls for the operation of the motor and the pump are provided at the front of the press, and since such structures are well known, a detailed description 40 herein is believed unnecessary.

Operation

45 In the operation of the press, the parts are normally maintained in the position illustrated in Figs. 1 and 2, with the rocker arm in the open position providing free access to the die area at the front of the press. The dies 21 and 22 may be anchored in position and this area is open for inspection and ready change of the die parts therein. After the work has been placed upon the dies, the pressure fluid is supplied to the top of the cylinders 25 and 26 and the pistons therein are moved downwardly, the stems 30 of the pistons pressing the toggle links 34 and 35 to their lower position, as illustrated in dotted lines in Fig. 2, thus swinging the rocker arm upon pivot 17 forwardly to the position indicated in dotted lines in Fig. 2. In the latter position, it will be observed that the pressure exerted by the pressure fluid downwardly against the pistons and equally, therefore, upwardly against the wall A', is counteracted by the downward pressure of the movable jaw 20 through the die parts 21 and 22. The toggle levers 35 operate through the rear open wall of the housing A, but are shielded from the front and sides by the walls 10, 11 and 12. By incorporating the cylinders and toggle levers within the base housing and by mounting the hydraulic supply on the side of the base, using multiple shear on the main rocker pin and toggles, an extremely small and compact press is achieved and in which the hydraulic pressure is low in ratio to the high die pressure attained by the use of the toggle action and leverage.

of the rocker arm. Very small pressure cylinders may thus be employed, with low hydraulic pressure and high die pressure attained by the toggle action and rocker arm leverage. The open jaw type design shown provides complete access to the die area and dies, thus adding to the larger output of work. The structure illustrated is substantially a one-piece unit and provides for fast-acting work output. The top wall of the housing not only provides the fixed jaw or die support, but also provides the suspension means for the power cylinders within the housing.

While, in the foregoing specification, I have set out specific structures in considerable detail for the purpose of illustrating an embodiment of the invention, it will be understood that such details of structure may be varied widely by those skilled in the art without departing from the spirit of my invention.

I claim:

1. In a press, a generally rectangular vertical hollow base having at least one open, vertically extending narrow side and vertically extending wide sides, a fixed jaw carried in the upper portion of said base between the vertically extending wide sides, a pivot pin supported in the upper portion of said base adjacent the said open side, a rocker arm pivotally carried intermediate the ends thereof by said pin and provided at one end with a jaw movable with the upper portion of said rocker arm toward said fixed jaw, said rocker arm having an integral depending arm portion extending downwardly along said open side of said base to substantially the bottom end of said base, a cylinder pivot pin within said hollow base and in the central upper portion thereof, a pressure-fluid, piston-equipped cylinder suspended upon said cylinder pivot pin and having a piston stem extending downwardly within said base, and a pair of toggle links each having one end pivotally connected together in the bottom portion of said base, one link being pivotally connected at its other end to the lower portion of said base remote from said open side and the other link being connected at its other end to the lower end of said depending rocker arm, the piston stem of said cylinder being connected to said toggle links adjacent their point of pivotal connection.

2. The structure of claim 1 in which said base and rocker arm are each equipped with a plurality of spaced-apart projections, each projection being equipped with an aperture with the apertures aligned and supporting the first-mentioned pivot pin, the rocker arm projections

being positioned between the base projections to develop multiple shear on said first-mentioned pivot pin.

3. The structure of claim 1 in which the rocker arm pivot pin is spaced more closely to the movable jaw end of said rocker arm than to the end of said rocker arm connected to said toggle links, said rocker arm being generally arcuate to provide portions thereof between said rocker arm pivot pin and said movable jaw end and between said rocker arm pivot pin and the toggle link-connected end that are in angled relation to each other and to provide a multiplying leverage while still maintaining the base and rocker arm in a compact space.

4. In a press having a generally rectangular vertical hollow base having at least one open, vertically-extending narrow side and vertically-extending wide sides, said base carrying a fixed jaw in the upper portion thereof between the vertically-extending wide sides, a cylinder pivot pin supported within said base in the central upper portion of said base and spaced laterally of said fixed jaw, a rocker arm pivot pin supported also in the upper portion of said base adjacent said open side, a pair of pressure-fluid, piston-equipped cylinders suspended upon said cylinder pivot pin, each cylinder having a piston stem extending downwardly within said base, a pair of toggle links in the bottom portion of said base for each cylinder, the links of each pair being pivotally connected together and to the piston stem of one of said cylinders, one of the links of each pair being pivotally mounted upon a pin carried in the lower portion of said base adjacent the side opposite the said open side and the other of the links in each pair having an end portion extending toward the open side of said base, a rocker arm pivotally carried by said rocker arm pivot pin and provided at its top with a jaw movable with said arm toward said fixed jaw for vertical pressing action and having a depending arm extending downwardly along said open side of said base and connected at its bottom to the end of the links in each pair extending toward said open side, and a vertical wall internally of said base between said cylinders.
